UNITED STATES PATENT OFFICE

2,441,144

WRENCH PROVIDED WITH CAM-ACTUATED
SELF-TIGHTENING JAWS

Roy L. Gregory, Everett, Wash.

Application May 29, 1945, Serial No. 596,517

1 Claim. (Cl. 81—91)

1

This invention relates to new and useful improvements in wrenches, and has for one of its objects the provision of a clinching device that is easily applied and tightened in operative position.

With this and other objects and advantages in view the invention further includes the following novel features and details of construction to be hereinafter more fully described, illustrated in the accompanying drawings and pointed out in the appended claim.

In the drawings:

Fig. 1 is a side elevation of an embodiment of the invention.

Fig. 2 is a perspective view thereof, showing a modified jaw insert, and

Fig. 3 is a perspective view of one of the removable jaw inserts.

Referring more in detail to the drawings, the numeral 5 designates the handle of the device.

The handle 5 is provided with an arcuate shaped bifurcated portion 7 in which is pivotally mounted a movable jaw 9 by means of a reduced end portion 11 of the jaw 9 and a pin 13.

The shoulder 15 formed at the termination of the reduced end portion 11 is shaped to conform to the portion 7 of the handle 5.

The jaw 9 is of convexo-concave shape and the concave portion thereof is provided with a recess 17 to receive the perforated ear 19 of the convex toothed insert 21 which is removably connected to the jaw 9 by a pin 23.

A jaw 25 having two convexo-concave shaped portions 27 and 29 is pivotally mounted by means of a pin 31 to the jaw 9.

The jaw 9 is provided with perforated projecting ears 33 forming therebetween a channel-shaped groove 12. The base of the groove 12 has a flat surface 14 that merges with a notch 14'. The notch 14' receives the perforated projecting lug 35 of the jaw 25 which is formed intermediate the concave portion of the jaw 25, and the pin 31 is positioned in the aligned perforations of the ears 33 and the lug 35, and the ears 33 conform to the shape of the jaw 25. The jaw 25 is likewise provided with a recess 17 in the concave portion thereof to receive the perforated ear 19 of the convex toothed insert 21 which is removably connected to the jaw 25 by a pin 23.

The jaw 25 is provided with a bore 37 opening into a flat surface 41' opposite the flat surface 14 of the jaw 9. These flat surfaces act as stop members limiting the closing action of the jaws 9 and 25. The bore 37 receives a spring 39 and pin 41 which bears against the flat surface 14 of

2

the jaw 9 and holds the jaws open when the jaws are not engaged.

The arcuate shaped portion 7 has a camming action between said portion and the lower concave portion 43 of the jaw 25, therefore by the movement of the handle 5 pressure is exerted on the jaws 9 and 25 to grip an article between the jaws.

The toothed inserts shown in Figs. 1 and 3 are for round objects but the insert 47 shown in Fig. 2 is for square or hex objects, or others of similar shape.

It will be understood, therefore, by those skilled in the art that the embodiment of the invention hereinafter disclosed provides a wrench having cam actions between certain portions thereof, which enables the wrench to be easily and quickly applied to an object and tightened thereon.

Having thus described the invention what is claimed as new and desired to be secured by Letters Patent is:

A wrench comprising a handle terminating in a cam portion, said cam portion having a convex surface and being bifurcated to form spaced ears, a first jaw having a concave seat adapted to receive interchangeable grip inserts, a reduced portion extending rearwardly from said jaw and fitted within said spaced ears, means pivotally securing said reduced portion and said ears together, a pair of spaced ears extending from said jaw adjacent said reduced portion and in a direction transversely of the concave seat, said spaced ears forming therebetween a channel-shaped groove, the base of said groove having a flat surface merging with a notch, a second jaw having a plurality of spaced concave portions facing in the same direction, one of said portions forming a seat adapted to receive interchangeable grip inserts for cooperation with corresponding grip inserts on the first jaw, the other of said concave portions on said second jaw forming a cam follower for contact by said cam portion, the working surfaces of the cam portion and said concave cam follower being substantially co-extensive in width, a pivot lug extending from said second jaw intermediate its concave portions and in the same facing direction thereof, said lug having a flat surface merging with a projection, said projection having a width substantially equal to the distance between and fitted within the spaced ears of the first jaw and into the notch thereof, pivot means pivotally connecting together said pivot lug projection and said first jaw spaced ears whereby the flat surfaces are opposite each other, said pivot means being supported substantially

throughout its length by said pivot lug projection and spaced ears, a bore in said second jaw extending transversely of said last mentioned means and located intermediate a concave portion and said projection of said second jaw and opening into the flat surface of said second jaw, a plunger in said bore adapted to contact the flat surface of said first jaw, a spring in said bore biasing said plunger into engagement with said first jaw flat surface whereby said jaws are biased to a spread-apart position and said cam follower into contact with said cam portion whereupon pivotal movement of said handle towards said second jaw moves said jaws together to grip objects therebetween.

ROY L. GREGORY.
